G. SCHNEGGENBURGER

PUMP WITH CAM CONTROLLED PLUNGERS

Filed June 25, 1926

Patented Jan. 4, 1927.

UNITED STATES PATENT OFFICE.

GÜNTHER SCHNEGGENBURGER, OF BERLIN-FALENSEE, GERMANY.

PUMP WITH CAM-CONTROLLED PLUNGERS.

Application filed June 25, 1926, Serial No. 118,572, and in Germany October 24, 1925.

This invention relates to an improved pump with cam-controlled plungers creating a uniform pump delivery of even smallest liquid quantities, which can be varied by suitable contrivances even with constant drive, means being provided for efficiently preventing the moved parts from running dry and seizing.

Heretofore, plunger pumps have become known which work with non-uniform plunger speeds after a sinuous curve. The pump delivery is, therefore, even with the arrangement of several cylinders, very non-uniform, and attempts have been made to attain a uniform pump delivery by an increase of the circumferential speeds. Apart from the fact that a satisfactory uniformity of the pump delivery is not attained thereby, there is no possibility of sufficiently lubricating the high-speed moved parts, so that a wear and working disturbances by seizing of the parts making contact with each other soon occurred. This results, of course, in a decrease of the working safety of the pump.

The present invention overcomes these drawbacks by imparting to the plungers a uniform speed in dependence upon lawfully constructed curves and providing means by which always a constant number of plungers discharge into the common pressure conduit. Furthermore, for attaining a reliable lubrication, all the moved parts, which might cause working disturbances by faulty lubrication, are set under pressure oil.

The accompanying drawing illustrates the subject matter of the present invention: Fig. 1 is a cross-section through a star-shaped arrangement of cylinders, on the line C—D of Fig. 2, which is a longitudinal section through said arrangement on the line A—B of Fig. 1; Fig. 3 is a side view of part of the non-revolvable cam shaft of the pump, and Fig. 4 is a cross-section through said shaft on the line E—F of Fig. 3 (the dotted curve α designating a cross-section on the line G—H of Fig. 3); Fig. 5 is a fragmentary side view of a modification of said cam shaft, and Fig. 6 is a cross-section through the latter on the line I—K of Fig. 5; while Fig. 7 is a fragmentary side view of another modification of said cam shaft, and Fig. 8 is a cross-section through the latter on the line L—M of Fig. 7.

In the pump casing 1 the plunger drum 2 is radially and axially mounted by means of

the covers 3 and 4 of said casing. The plunger drum is set in rotation by means of the worm shaft 5 and worm wheel 6. In the plunger drum, and in two parallel planes at right angles to the drum axis, a fuel pump system with the plungers 7, 7^a, 7^b, 7^c is combined with a lubricant pump system with the plungers 8. The plungers positively receive their pressure stroke by their sliding contact with the cam 9 of the non-revolvable cam shaft 10, while the suction stroke is exerted by the cylindrical coil springs 11 acting upon the plungers.

The cam curves $a-b$ and $c-d$ of the cam shaft are branches of an Archimedean spiral, while $b-c$ and $d-a$ are circular arcs. In the pump illustrated, for instance, the pressure curves $a-b$ lie within a sector of 180° , the circular arc $b-c$ within a sector of 45° , the suction curve $c-d$ within a sector of 90° , and the circular arc $d-a$ within a sector of 45° . With a star-shaped arrangement of four cylinders at right angles to one another, thus, in any position of the plunger drum always one plunger exerts the suction stroke while always two plungers at a time exert the pressure stroke. In the position illustrated in Fig. 1, the plunger 7 begins with the pressure stroke at the moment when the plunger 7^b has finished the same. In the circular sections $d-a$ and $b-c$ the plungers remain in the inner and outer dead-point positions. As at any moment of the pump rotation always a constant number of plungers discharge into the pressure conduit, it follows that, since the plunger speed according to the construction of the pressure curve is uniform, not only during a stroke interval but during the whole delivery period a uniform pump delivery is attained.

The cam of the cam shaft is conical in such a way that within the sectors $a-b$, $b-c$, $c-d$, and $d-a$, the same kinds of curves are maintained but with the difference that the Archimedean spiral branches $a-b$ and $c-d$ run flatter and the circular arc $b-c$ has smaller radii.

If the cam shaft is axially displaced in one or the other direction by means of the adjusting lever 12 and the screw-gearing 13, both pumps exert smaller or larger strokes respectively. The cam shaft is locked against rotation by means of a disc like spring 14 and groove 15 and thus maintains always the same position with reference to the suction

and pressure channels in the pump casing. The plungers will suck during the suction period fuel and lubricant through the admission ports 16 and 16^a and the suction channels 17 and 17^a and deliver this during the pressure period through the pressure channels 18 and 18^a and through the pressure ports 19 (and 19^a, not shown) to the places of consumption. In communication with the lubricant pressure channel is the lubricating groove 20 that leads pressure oil into the ring channels 21 and 21^a and through the grooves 22 and 22^a into the interior 23 of the pump casing 1, where it is distributed through the longitudinal grooves 24 into the labyrinth grooves 25 of the fuel plungers. By the arrangement of said lubricating grooves 20-25, all parts coming in contact with the fuel and in sliding contact with each other are continuously lubricated in an effective way by the oil under pressure.

Furthermore, by a convenient choice of the ratio between the oil pressure in the interior of the pump casing and the fuel pressure in the cylinders, a continuous slight overflowing of lubricant into the interior of the pump cylinders can take place. Whereas thereby the safety of the pump working is considerably increased, the oil addition to the fuel in the motor working is much desired. Difficulties, similar to those afore-described, in the working of the fuel pump in the interior of the motor are done away by said oil addition. Particularly, the plungers, the cylinder walls, and the valves are thereby coated with a slight oil film and thus sticking valve rods, burning of the valves, and plunger ring breakings are effectively avoided. Furthermore, the fuel is prevented by the oil in the interior of the pump casing from escaping from the pump through untight joints of casing parts or through the bearings of the driving shaft.

Of course, in each of the two pump systems and in the same or in parallel cylinder planes, further plungers can be used, provided that the condition is accomplished: that all said cylinders produce a perfectly uniform pump delivery. In this case, cam shafts such as shown in Figs. 5-8 must be employed. The pump cylinders of the fuel or lubricant system in Figs. 5 and 6 are arranged in one plane, and those in Figs. 7 and 8 in two planes parallel to one another. For, in these cases, a simple duplication only and no change of the mode of operation forming the subject matter of the present invention, is required. It is also immaterial how many plungers are actuated at a time by one pressure curve section of the cam shaft, it being essential only for the idea of the present invention that at any moment always a constant number of plungers dis-

charge into the pressure conduit with a uniform plunger movement.

The arrangement of the cylinders, either in star shape as illustrated, or in series beside each other and at right angles to the cam shaft, or in a circle and parallel around the cam shaft, is also immaterial, all this being appropriate constructional forms of the idea of the present invention only.

The arrangement may, of course, also be such that the plungers are not arranged in a rotary drum but in a stationary framing while the cam shaft is revolvable; this being obviously understood without further illustration.

Furthermore, it is not absolutely necessary that the fuel pump is combined with the lubricant pump in one casing. The same effect is attained if the pressure oil of a separately arranged lubricant pump is introduced into the casing of a fuel pump; the arrangement combined in one casing as illustrated being, of course, preferred for obvious reasons.

The idea of the invention is not limited to fuel pumps but it can, for instance, also be applied to feed pumps of rapid steam generators, for the delivery of feed water and of heating oil.

What I claim, is:—

1. In a plunger pump, the combination of a pump casing, a rotary plunger drum therein comprising a plurality of cam-controlled plungers, and a non-revolvable cam shaft acting upon said plungers and having a cam curve designed to create at any moment a pump delivery by a constant number of plungers with a uniform plunger movement.

2. A plunger pump as specified in claim 1, in which said cam shaft is axially adjustable and thereby adapted to vary the strokes of all said plungers without impeding the dependence of the latter upon each other and their uniform movement.

3. In a plunger pump as specified in claim 1, means by which said pump casing is continuously filled with pressure oil during the working of the pump.

4. In a plunger pump as specified in claim 1, in which said plungers belong to a fuel pump system and to a lubricant pump system; a common driving shaft for both said pump systems.

5. In a plunger pump as specified in claim 1, in which said plungers belong to a fuel pump system and to a lubricant pump system; means to vary the plunger strokes of both said pump systems at a time in dependence upon one another.

In testimony whereof I have hereunto set my hand.

GÜNTHER SCHNEGGEBURGER.
